DRAIN LINE CLEANER

Charles Lundelius, Rocklin, Calif.

Application September 21, 1946, Serial No. 698,469

2 Claims. (Cl. 15—104.3)

1

This invention relates to means for cleaning out drain lines of various kinds, such as septic tank drainage lines and the like.

The object of the invention is to produce a drain line cleaner which will have sufficient weight and be of such shape as to readily clear the cross tile openings in septic tank drainage lines and break up and flush away accumulated deposits tending to clog the line.

While of particular adaptability to septic tank drainage lines, the device can of course be used on any type of sewage or other disposal lines.

A further object of the invention is to produce a device which will readily pass around sharp bends in the disposal pipes, even those having as high as a 45° bend, though primarily it is intended for use on straight lines.

A further object of the invention is to provide a simple and inexpensive device, and yet one which will be exceedingly effective for the purpose for which it is designed.

These objects are accomplished by means of such structure and relative arrangement of parts as will fully appear by a perusal of the following specification and claims.

In the drawings:

Fig. 1 is a side elevation of my improved cleaner, showing it as attached to a hose line.

Fig. 2 is a longitudinal section of the cleaner.

Fig. 3 shows a modified form of attachment for the cleaner from that shown in Fig. 2.

Referring now more particularly to the characters of reference on the drawings, the numeral 1 designates a plug which is made of relatively heavy metal, and is of a slightly oval contour longitudinally thereof. At one end the plug 1 is provided with threads 2 for connection with a hose 3. The plug 1 from the threaded portion 2 to its outer end is provided with a central orifice 4 which terminates at its outer end in a threaded portion 5 for the reception of either a solid bull point 6 or a screw point 7, which may be interchangeably used with the plug 1 as conditions may necessitate. Towards the forward end the plug 1 is provided with a series of circumferentially disposed orifices 8 which communicate from the central orifice 4 and project in a forward direction towards the outer end of the plug.

When the device is to be used it is attached to the hose 3 and said hose is projected into the drain line, with water under considerable force flowing through the hose, through the central orifice 4, and out the orifices 8. The weight and shape of the plug 1 is such that it will readily force its way through accumulated material in the drain line, the initial point of entry being made either by the bull point 6 or by the screw point 7, according to which is being used, and which latter are used interchangeably according to the material to be broken through.

2

The force of the water discharging ahead of the plug, the weight of the plug, and the pressure given to the plug by an alined push against the hose 3 will very adequately break through and dislodge accumulated material in the line and clean the same. The length of the plug is such that it will readily clear tile openings in septic tank drainage lines, or joints of any character in other lines, and the curving outer side walls of the plug are such that the same may be readily withdrawn through the line without striking or getting caught on any projections therein.

From the foregoing description it will be readily seen that there has been produced such a device as substantially fulfills the objects of the invention, as set forth herein.

While this specification sets forth in detail the present and preferred construction of the device, still in practice such deviations from such detail may be resorted to as do not form a departure from the spirit of the invention, as defined by the appended claims.

Having thus described the invention, the following is claimed as new and useful, and upon which Letters Patent are desired:

1. A drain line cleaning device comprising the combination of a flexible water hose, a plug connected to the outer end of the hose and provided with a longitudinal bore in register with the bore of the hose, such plug comprising a relatively short heavy body, the outer side surface of the body being smooth and uninterrupted over its entire area, a solid material piercing element fixed to and projecting outwardly from the outer end of the body, such element throughout its length being of materially lesser cross sectional diameter than the plug, the forward part of the body to the rear of the front end thereof being provided with a series of forwardly directed circumferentially disposed discharge orifices which are in register with the interior bore of such body.
2. A device as in claim 1 in which the body is of oval shape in longitudinal cross section.
